SPEED CONTROLLER FOR HYDRAULIC MOTORS

James K. Douglas, Milwaukee, Wis., assignor to
The Oilgear Company, Milwaukee, Wis., a corporation of Wisconsin

Application December 24, 1934, Serial No. 758,966

14 Claims. (Cl. 60—52)

This invention relates to a hydraulic transmission in which the motor is driven at a predetermined speed whenever the pump is operating at a constant speed and constant displacement. More particularly, it relates to an apparatus for maintaining the motor speed constant, such as the apparatus disclosed in Patent No. 2,004,522 issued June 11, 1935 on an application filed September 19, 1932, Serial No. 633,750, of which this application is a continuation in part.

The pump has as an inherent characteristic thereof an internal slip or leakage which reduces its net delivery. This slip is made up of several small factors, such as the small volumes which escape from between the cylinders and the pump valve, the small volumes which pass across the face of the pump valve from the discharge port to the intake port thereof, and any small volumes which may leak past the pistons. In addition, the net delivery of the pump is decreased by an apparent slip due to deflection of its parts, expansion of the pipes into which it delivers its output and to the compressibility of the driving liquid, which is ordinarily a good grade of lubricating oil.

If the motor is of the rotary type, it has a slip composed of substantially the same factors which compose the slip of the pump. If the motor is of the reciprocating type, its slip is due principally to any liquid which may escape past the motor piston.

Due to the compressibility of the liquid and to the fact that liquid will escape at an increased rate in response to an increase in pressure, the slip of both the pump and the motor at any given temperature will increase as the pump pressure increases and decrease as the pump pressure decreases. Consequently, the speed of the motor will decrease as the pressure increases and increase as the pressure decreases unless provision is made to compensate for variations in the combined slip of the pump and the motor due to variations in pressure.

The slip of both the pump and the motor is also affected by variations in temperature due to the fact that the fluidity of the oil ordinarily employed as a driving medium increases as the temperature increases and decreases as the temperature decreases and to the fact that certain co-acting pump parts ordinarily have different coefficients of expansion so that an increase in temperature will cause one part to expand more rapidly than another part and thereby vary the clearance therebetween. Consequently, the combined slip of the pump and the motor will vary in ac-

cordance with variations in temperature and cause the speed of the motor at any given pressure to decrease as the temperature of the oil increases and to increase as the temperature of the oil decreases unless provision is made to compensate for variations in the combined slip due to variations in the temperature of the oil.

The above patent discloses an apparatus which will compensate for variations in slip due to variations in pressure and an apparatus which will compensate for variations in slip due to variations in both temperature and pressure. Each apparatus is provided with a plurality of control elements each of which is individually adjustable and, in order that the apparatus may be preset or adjusted at the factory, certain data are necessary such as the character of the oil to be employed, the temperature limit, the maximum working pressure and the amount of slip.

The present invention has as an object to provide an apparatus which is an improvement over the patented apparatus.

Another object is to provide a speed controlling apparatus in which a plurality of control elements are adjustable simultaneously.

Another object is to provide a speed controlling apparatus which may be adjusted without previous knowledge of all conditions under which it is to operate.

Another object is to provide a speed controlling apparatus which is susceptible of close adjustment and control.

Another object is to provide a speed controlling apparatus which is positive and precise in operation.

Other objects and advantages will appear from the following description of the apparatus illustrated in the accompanying drawings which are somewhat diagrammatic in character and in which the views are as follows:

Fig. 1 is a top plan view of a slip compensator in which the invention is embodied.

Fig. 2 is a sectional plan view of the slip compensator, the section being taken substantially along the line 2—2 shown extending through Figs. 3, 4 and 5.

Fig. 8 is a vertical section taken on the line 8—8 of Fig. 1.

Fig. 9 is a vertical section taken on the line 9—9 of Fig. 2 with certain parts shown in elevation.

Fig. 10 is a sectional plan view taken on the line 10—10 of Fig. 9 but shown turned at an angle 10 to the disclosure of Figs. 2 and 9.

Fig. 11 is in part a diagram of a hydraulic circuit containing a hydraulic motor the speed of which is to be controlled and in part a schematic drawing showing the relation of the several parts 15 of the slip compensator to each other and to the hydraulic circuit.

The slip compensator, as shown, consists primarily of a pressure inverter A, a resistance B consisting of a choke and an orifice connected 20 in series with each other and connected to the pressure inverter A, a constant pressure valve C connected in parallel with the pressure inverter A, a temperature responsive resistance valve D connected in series with the valve C, and a throttle E connected in series with the temperature responsive resistance valve D, all of which are arranged in a casing 11 having an inlet 12 (Fig. 3) and an outlet 13 (Figs. 1 and 8).

For the purpose of illustration, the slip compensator is shown in Fig. 11 as being connected 30 to a hydraulic transmission consisting of a pump 14 and a motor 15 which are connected to each other by two pipes 16 and 17 having a reversing valve 18 connected therein. Liquid is discharged 35 by the pump into the pipe 16 and liquid is returned from the motor to the pump through the pipe 17. The slip compensator has its inlet 12 connected to the pipe 16 by a pipe 19 and its outlet 13 connected to the pipe 17 by a pipe 20.

The pressure inverter A (Figs. 3 and 6) is arranged in a vertical bore 21 which is formed in the casing 11 and communicates at its lower end through an annular valve seat 22 with the inlet 12.

The lower end of the bore 21 is connected by a 45 passage 23 (Fig. 6) to the lower end of a vertical bore 24 which is formed in the casing 11 and contains the resistance B.

The bore 24 is closed at its lower end by a plug 25 and connected intermediate its ends by 50 a passage 26 (Fig. 7) to a vertical bore 27 which is formed in the casing 11 and contains the constant pressure valve C.

The bore 27 is closed at its lower end by a cap 28 fastened to the bottom of the casing 11, 55 and the bores 21, 24 and 27 are closed at the upper ends thereof by a cap 29 fastened to the top of the casing 11.

Liquid entering the inlet 12 may flow through 60 the pressure inverter A and the passage 23 into the resistance B and be discharged from the resistance B into the passage 26.

The bore 27, at a point opposite the passage 26, is connected by a passage 30 (Fig. 8) to the lower end of a vertical bore 31 which contains 65 the throttle E and is open to the outlet 13 at a point opposite the passage 30. The passage 26, the bore 27, the passage 30, and the bore 31 provide a channel through which liquid exhausted from the resistance B may escape freely through the 70 outlet 13.

The inlet 12 is connected to the bore 27 by a passage 32 (Fig. 3) which extends horizontally from the inlet, then vertically upward and then horizontally and enters the bore 27 at a point a 75 short distance below the upper end thereof.

The upper end of the bore 27 is open to a passage 33 (Fig. 4) which is formed in the cap 29 and communicates with a vertical passage 34 formed in the casing 11. The lower end of the passage 34 communicates with a horizontal passage 35 which has one of its ends open to the bore 27 at the lower end thereof and its other end open to a vertical bore 36 formed in the lower part of the casing 11.

The bore 36 contains a part of the temperature 10 responsive resistance valve D which controls communication between the passage 35 and a chamber 37 (Figs. 5 and 8) which is formed in the casing 11 and closed by a cap plate 38 fastened to the end of the casing.

The chamber 37 communicates with the bore 31 through a smaller bore 39 which is concentric with the bore 31 and has a part of the throttle E fitted therein.

Liquid may flow from the inlet 12 through the 20 passage 32, the constant pressure valve C, the passages 34 and 35, the bore 36, the temperature responsive resistance valve D, the chamber 37 and the throttle E to the outlet 13. The valve C keeps the pressure of the liquid entering the 25 valve D substantially constant, the valve D responds to variations in temperature to vary the volume which may flow therethrough, and the throttle E restricts the flow of liquid into the outlet 13.

Pressure inverter A

As best shown in Figs. 3 and 6, the bore 21 has fitted in the upper part thereof a hollow piston A¹ which has a valve stem A² extending through its lower end wall or head and forming an oil-tight joint therewith. The stem A² extends through the valve seat 22 and carries a valve A³ upon its lower end to coat with the seat 22 and thereby control the flow of liquid from the inlet 12 to the passage 23.

The piston A¹ is urged downward by a helical compression spring A⁴ which is arranged inside the same and has its tension adjusted by a screw A⁵ threaded through the cap 29. In order that the spring may not tend to tilt the piston in 45 the bore, it is preferably arranged between two spring retainers which are pivoted, respectively, upon the ends of the stem A² and the screw A⁵, as shown in Figs. 3 and 6.

The downward movement of the piston A¹ is 50 limited by an annular shoulder A⁶ which is formed in the wall of the bore 21 and against which the spring A⁴ tends to hold the piston A¹ to thereby tend to maintain the opening between the valve A³ and the valve seat 22 at a predetermined 55 maximum.

As previously explained, the inlet 12 is connected to the discharge side of the pump 14 and the outlet 13 is connected to the intake side of the pump. Consequently, the slip compensator permits liquid to be bypassed at limited rates across the two sides of the hydraulic circuit and pump pressure prevails at the inlet 12.

The flow of liquid through the pressure inverter is retarded initially by the resistance B which 65 causes pressure to build up in the lower end of the bore 21 and act upon the lower end of the piston A¹. The force exerted upon the piston A¹ by the liquid in the lower end of the bore 21 and the force exerted upon the lower face of the valve A³ by the pressure at the inlet tend to move the piston A¹ 70 upward against the resistance of the spring A⁴.

In order that movement of the piston A¹ may 75 not be hampered by entrapped air or liquid, the

upper end of the bore 21 may be opened to the atmosphere but it is preferably connected to the return side of the hydraulic circuit so that the upper end of the piston A¹ is subjected to the pressure that prevails in the return side of the circuit. Ordinarily, the upper end of the bore 21 is connected to the passage 26 by a passage 40.

When the pump has created a predetermined low pressure, the combined force exerted by the liquid upon the piston A¹ and upon the valve A³ is sufficient to raise the piston A¹ and reduce the opening between the valve A³ and the valve seat 22, thereby throttling the flow of liquid into the bore 21 and causing a pressure differential between the inlet 12 and the lower end of the bore 21.

As the pump pressure increases, the force exerted by the liquid upon the valve A³ will increase in proportion and move the valve A³ nearer the seat 22, thereby increasing the throttling effect and causing the pressure in the lower end of the bore 21 to decrease as pump pressure increases. Consequently, the pressure of the liquid delivered to the resistance B will vary inversely in proportion to variations in pump pressure.

The area of the valve A³ is not great enough to permit the liquid at the inlet to exert a great enough force, at maximum pump pressure, to compress the spring A⁴ enough to permit the valve A³ to seat firmly upon the seat 22. In other words, the force exerted upon the valve A³ by the high pressure liquid at the inlet must be augmented by a force exerted upon the lower face of the piston A¹ by the low pressure liquid in the lower end of the bore 21 in order to overcome the resistance of the spring A⁴. If a sudden rush of pressure should cause the valve A³ to close, the pressure in the lower end of the bore 21 would drop and permit the valve to immediately reopen.

40 Resistance B.

The resistance B consists of a choke and an orifice which are shown connected in series with each other for the reason that this arrangement produces the desired result when the slip compensator is connected to a pump of the type ordinarily employed in installations in which it is desired to drive the machine or a part thereof at a constant speed during a given period of time.

50 The slip of this type of pump does not vary wholly in accordance with the law of viscous flow nor wholly in accordance with the law of turbulent flow but varies at a rate which may be readily obtained by connecting a choke and an orifice in series.

However, it is to be understood that the resistance B may consist of either a choke, an orifice, a choke and an orifice in parallel, or a choke and an orifice in series, depending upon the characteristics of the slip of the transmission to which the slip compensator is to be connected.

As shown in Figs. 2, 6, 7, 9, and 10, the resistance B is provided with a cylindrical sleeve B¹ which is tightly fitted in the bore 24. The sleeve B¹ is provided in its lower part with a bore B² and in its upper part with a counterbore B³ which forms an annular shoulder B⁴ in the wall of the sleeve B¹ at its junction with the bore B².

The sleeve B¹ extends from a point near the top 70 of the bore 24 to a point just above the entrance to the passage 23 (Fig. 6) so that liquid passing through the passage 23 from the inverter A is directed into the bore B² which has a hollow cylindrical member B⁵ closely fitted therein with its lower end open to the passage 23.

The member B⁵ has a slot B⁶ (Figs. 7 and 10) formed in its side wall and partly in registry with an elongated slot B⁷ which is formed in the sleeve B¹ and extends from a point just above the bottom of the sleeve B¹ to a point a substantial distance above the shoulder B⁴, as shown in Fig. 6. 5

The wall of the member B⁵ ordinarily covers a part of the slot B⁷ so that the edges of the slots B⁶ and B⁷ define a restricted passage or orifice B⁸ (Figs. 7 and 10) through which liquid discharged from the passage 23 must pass. The cross-sectional area of the orifice B⁸ may be varied by rotating the member B⁵ to vary the width of the orifice or by moving the member B⁵ vertically to vary the length of the orifice. 10 15

The member B⁵ is supported by a bolt B⁹ which extends through the upper wall thereof and is threaded into a cylindrical choke member B¹⁰ arranged in the upper part of the sleeve B¹. The member B⁵ is normally fixed for axial movement 20 with the choke B¹⁰ by the bolt B⁹ which may be loosened to permit the member B⁵ to be rotated to vary the width of the orifice B⁸.

The choke member B¹⁰ has its upper part closely fitted in the counterbore B³ and its lower part reduced in diameter and closely fitted in the bore B², an annular shoulder B¹¹ being formed upon the periphery of the member B¹⁰ between the upper and the lower parts thereof. 25

The shoulder B¹¹ is spaced above the shoulder B⁴ to provide between the periphery of the choke member B¹⁰ and the wall of the counterbore B³ a restricted passage B¹² which functions as a choke. The choke passage B¹² is open at one point to the slot B⁷ in the sleeve B¹ (Fig. 6) and at another 35 point it communicates with an aperture B¹³ (Fig. 7) which is formed in the wall of the sleeve B¹ and registers with the passage 26. 30

Choke member B¹⁰ is supported by a stem B¹⁴ which is threaded therein and extends through 40 cap 29 and through a gland 41 fastened to cap 29. Stem B¹⁴ is provided with means for rotating it, as by having its upper end slotted, and it is restrained from axial movement as by having two collars fixed thereon and in contact, respectively, 45 with the lower face of cap 29 and the upper face of gland 41.

Rotation of the stem will raise or lower the choke member B¹⁰ and vary the distance between the shoulders B⁴ and B¹¹, thereby varying the 50 cross-sectional area of the passage B¹² to vary the volume of liquid which can flow therethrough at any given pressure.

Rotation of the stem B¹⁴ will also raise or lower the cylindrical member B⁵ and thereby vary the 55 cross-sectional area of the orifice B⁸ by varying the length thereof.

The choke and the orifice may thus be simultaneously adjusted by simply rotating the stem B¹⁴. Also, the relation between the choke and the 60 orifice may be varied by rotating the cylindrical member B⁵ as previously explained.

The choke member B¹⁰ is prevented from rotating by a key B¹⁵ (Figs. 2 and 9) fixed therein and closely fitted for vertical movement in a complementary keyway which is formed in the wall of the sleeve B¹ and has sufficient length to permit the member B⁵ to move vertically a substantial distance. 65

The slot B⁷ and the aperture B¹³ are formed 70 close together in the sleeve B¹ at one side of the choke member B¹⁰, and the key B¹⁵ is arranged in the same side of the member B¹⁰ and extends across the choke passage B¹² between the slot B⁷ and the aperture B¹³ to seal it therebetween. 75

Thus, as viewed in Fig. 2, the choke passage B^{12} extends from the left edge of the slot B^7 around the member B^{10} to the right edge of the aperture B^{13} . Its length is fixed but its cross-sectional area may be varied by varying the distance between the shoulders B^4 and B^{11} as previously explained.

Liquid entering the bore 24 from the pressure inverter A flows through the orifice B^8 (Figs. 7 and 10) at a relatively high speed and then flows upward at a reduced speed through the slot B^7 (Fig. 6) due to the cross-sectional area thereof being much greater than the area of the orifice B^8 . From the slot B^7 , the liquid flows through the choke passage B^{12} , the aperture B^{13} (Fig. 7), the passage 26 , the bore 27 , the passage 30 (Fig. 8), the bore 31 and the outlet 13 to the return pipe 20 .

Constant pressure valve C

The bore 27 (Figs. 2, 3 and 4) has a plunger C^1 fitted in the lower part thereof to reciprocate therein and a plug C^2 rigidly secured in the upper part thereof and provided with an axial bore C^3 and with a plurality of radial ducts C^4 which intersect the bore C^3 at a point intermediate the ends thereof.

The outer ends of the ducts C^4 open into an annular groove C^5 which is formed in the periphery of the plug C^2 and registers with the upper end of the passage 32 (Fig. 3) so that liquid may flow from the inlet 12 into the bore C^3 .

Communication between the bore C^3 and the ducts C^4 is controlled by a valve C^6 which is fitted in the bore C^3 and has its head supported by the reduced upper end of the plunger C^1 so that raising the plunger C^1 a greater or lesser distance will cause the flow of liquid into the bore C^3 to be cut off or restricted. The bore C^3 ordinarily has suitable bushings fixed therein above and below the intersection with the ducts C^4 to provide a bearing for the valve C^6 .

The plunger C^1 and the valve C^6 are urged downward by a helical compression spring C^7 arranged in the bore 27 between two spring retainers C^8 and C^9 which bear, respectively, against the reduced lower end of the plug C^2 and upon the head of the valve C^6 in order to retain the head of the valve C^6 in contact with the plunger C^1 and to prevent the spring from bearing unevenly upon the plunger C^1 and thereby tending to tilt it in the bore 27 .

As previously explained, liquid discharged from the resistance B flows through the bore 27 from the passage 26 to the passage 30 both of which connect with the bore 27 between the plunger C^1 and the plug C^2 as shown in Figs. 7 and 8. Therefore, the action of the spring C^7 is supplemented by the action of this discharge liquid upon the upper end of the plunger C^1 . The liquid discharged from the resistance B may have a negative or zero pressure but it ordinarily has a low positive pressure due to the fact that the pump 14 ordinarily has connected therewith an auxiliary pump (not shown) which delivers liquid into the intake side of the pump at a constant low pressure to compensate for leakage losses and it thereby maintains a constant low pressure in the pipes 17 and 20 and in the passages 26 and 30 .

When the plunger C^1 is in its lower position, liquid may flow freely from the passage 32 through the ducts C^4 , the bore C^3 and the passages 33 , 34 and 35 into the lower ends of the bores 27 and 36 .

Discharge of liquid from the bore 36 is resisted

by the temperature responsive resistance valve D , and this resistance causes pressure to be created in the lower ends of the bores 27 and 36 . This pressure acts upon the lower end of the plunger C^1 and urges it and the valve C^6 upward with a force proportional to the difference between the pressure in the lower end of the bore 27 and the pressure in the bore 27 above the plunger C^1 .

Upward movement of the plunger C^1 causes the valve C^6 to throttle the flow of liquid from the ducts C^4 into the bore C^3 and thereby causes a drop in pressure therebetween.

As the pressure at the inlet 12 rises, the pressure in the lower end of the bores 27 and 36 will rise until the drop in pressure across the plunger C^1 reaches a value corresponding to the resistance of the spring C^7 at which time the liquid in the lower end of the bore 27 has raised the plunger C^1 until the valve C^6 produces sufficient throttling effect to maintain the pressure in the lower ends of the bores 27 and 36 at the value determined by the resistance of the spring C^7 . Therefore, when the slip compensator is functioning, liquid is being delivered to the temperature responsive resistance valve D at a substantially constant low pressure.

While the resistance of a spring increases as it is deflected, the distance through which the valve C^6 is moved after the valve D opens is so short that the increase in the resistance of the spring C^7 is negligible or substantially so and has little effect on the pressure at which liquid is delivered to the valve D . If this very slight increase in the resistance of the spring C^7 should cause an appreciable variation in the rate of flow through the temperature responsive part of the slip compensator, it may be readily compensated for by adjustment of the pressure responsive part of the slip compensator.

Temperature responsive resistance valve D

The flow of liquid from the passage 35 (Fig. 4) to the outlet 13 is retarded in the first instance by a ball valve D^1 (Fig. 5) arranged within the chamber 37 upon an annular valve seat D^2 which is threaded into the bore 36 and through which the passage 35 communicates with the chamber 37 .

The ball valve D^1 is urged against the seat D^2 by a helical compression spring D^3 arranged partly in the upper end of the bore 36 and partly in the chamber 37 between a screw plug D^4 , which closes the upper end of the bore 36 , and a socket D^5 which bears upon the ball valve D^1 and through which the spring exerts a force thereon.

The action of the spring D^3 upon the valve D^1 is modified by a temperature responsive device such as a bimetallic strip D^6 (Figs. 5 and 8) which is arranged in the chamber 37 and immersed in the liquid which flows past the valve D^1 . The strip D^6 is wound in a spiral and has one of its ends in engagement with the socket D^5 and its other end fixed to a stationary pin D^7 fixed to the casing 11 .

The function of the device D^6 is to vary the spring pressure upon the valve D^1 in response to variations in the temperature of the liquid. It may either increase the pressure upon the valve in response to an increase in temperature or it may offer an initial resistance to the action of the spring D^3 and then decrease that resistance in response to an increase in temperature, thereby varying the flow of liquid past the

valve D¹ inversely to variations in the temperature of the liquid.

Throttle E

5 The discharge of liquid from the chamber 37 to the outlet 13 is controlled by a valve E¹ (Figs. 5 and 8) which is closely fitted in the bore 39 and fixed at its upper end to a screw E² which is considerably larger in diameter, threaded into 10 the bore 31 and provided with a gland E³ to prevent leakage of liquid.

15 The valve E¹ is provided in its lower end with one or more tapered grooves E⁴ which, together with the wall of the bore 39, form small orifices 20 through which liquid may flow at limited rates from the chamber 37 to the outlet 13. The area of the orifices may be varied by turning the screw E² to raise or lower the valve E¹.

25 The throttle E restricts the flow of liquid from the chamber 37 to the outlet 13 and thereby causes a higher pressure to prevail in the chamber 37 than prevails in the outlet 13. The rate of flow through the orifices E⁴ is a function of the difference in pressure upon opposite sides thereof.

30 When the temperature of the liquid is at a predetermined minimum, the valve D offers a predetermined minimum resistance to the flow of liquid therethrough and thereby permits a predetermined maximum pressure to be created in the chamber 37 so that liquid flows at a predetermined maximum rate through the throttle E.

35 As the temperature of the liquid rises, the valve D offers increased resistance to the flow of liquid therethrough with a resultant drop in the pressure in the chamber 37. As the pressure in the chamber 37 decreases, the flow of liquid through the throttle E decreases, thereby varying 40 the flow inversely to variations in the temperature of the liquid.

Operation

45 Assuming that the slip compensator is connected to a hydraulic transmission as shown in Fig. 11, that the pump 14 is delivering liquid to the motor through the pipe 16 and that the motor is returning liquid to the pump through the pipe 17, liquid will be bypassed at a limited 50 volumetric rate from the pipe 16 through the slip compensator to the pipe 17.

This liquid will enter the inlet 12 at pump pressure, pass through the slip compensator and be returned to the pump at the constant low 55 pressure prevailing in the return pipe 17.

The reason for directing the discharge from the slip compensator into the return pipe 17 is that the combined slip of the pump and motor varies directly in accordance with variations in 60 the drop in pressure across the motor or between the discharge pipe 16 and the return pipe 17. It is for this reason that the upper surfaces of the plungers A¹ and C¹ are subjected to return pipe pressure and are each urged downward by a 65 force proportional thereto.

If the motor discharged into a reservoir and the pump received liquid from the reservoir at atmospheric pressure, the slip compensator could discharge into the reservoir and it would not 70 be necessary to subject the pistons A¹ and C¹ to the return pressure but simply to provide vents above the pistons A¹ and C¹. Therefore, the liquid pressure acting upon the upper surfaces of the pistons A¹ and C¹ has been disregarded 75 in the explanation given herein.

The liquid to be bypassed flows from the pipe 16 through the pipe 19 into the inlet 12 at pump pressure and in a single stream as indicated by the arrow superimposed upon the pipe 19 in Fig. 11.

5 After passing through the inlet 12, the liquid is divided into two streams. One stream flows through the pressure inverter A and the resistance B, as indicated by left half-arrows, and has its rate of flow varied inversely to variations in 10 pump pressure. The other stream flows through the constant pressure valve C, the temperature responsive resistance valve D, and the throttle E, as indicated by the right half-arrows, and has its rate of flow varied inversely to variations in its 15 temperature. The two streams are united at the outlet 13 and returned to the pump at the return pressure and in a single stream, as indicated by the full arrows superimposed upon the pipe 20.

20 When the pump pressure rises above a predetermined minimum, the piston A¹ is raised by the liquid pressure so that the valve A³ throttles the flow through the valve seat 22 to reduce the pressure in the lower end of the bore 21 in proportion to the rise in pump pressure above that minimum. 25 If pump pressure fluctuates, the inverter A will vary the pressure in the lower end of the bore 21 and in the passage 23 inversely to variations in pump pressure as previously explained.

From the pressure inverter A, the liquid flows 30 through the resistance B at a rate which varies according to variations in the pressure at which liquid is delivered thereto and, since this pressure varies inversely to pump pressure, the flow through the resistance B will vary inversely to 35 pump pressure.

By adjusting the relation between the orifice B⁸ and the choke passage B¹² to obtain a flow corresponding to the variation characteristics of the slip of the transmission and then turning the 40 screw B¹⁴ to adjust the total amount of orifice and choke effect to correspond to the amount of slip of the transmission due to variations in pressure, the flow of liquid through the inverter A and the resistance B will be varied inversely at 45 exactly the same rate at which the slip of the transmission varies in response to variations in pump pressure, thereby maintaining the speed of the motor 15 constant at any given temperature regardless of any and all changes in pump pressure. 50

In order that the speed of the motor 15 may be maintained constant throughout the entire range of operating pressures and temperatures, the flow through the slip compensator must also be varied 55 inversely to variations in the slip of the transmission due to variations in the temperature of the liquid. This is accomplished by the valves C and D and the throttle E which function as follows:

Before pump pressure reaches a predetermined 60 minimum, it extends through the passage 32 (Figs. 3, 4 and 11) the ducts C⁴, the bore C³ and the passages 33, 34 and 35 into the lower ends of the bores 21 and 36. The valve D resists the escape of liquid from the lower end of the bore 36 and 65 enables the pressure to act upon the lower face of the plunger C¹.

When pump pressure rises above the predetermined minimum, the force exerted by the liquid upon the plunger C¹ is sufficient to raise it and the 70 valve C⁶ against the resistance of the spring C⁷. The valve C⁶ throttles the flow from the ducts C⁴ to the bore C³ and causes a drop in pressure therebetween.

As the pump pressure continues to rise, the 75

force exerted by the liquid upon the plunger C¹ increases and the valve C³ continues to rise and increase its throttling effect until it is permitting passage of only sufficient liquid to maintain a predetermined low pressure in the lower ends of the bores 27 and 36. The valve C thus functions as a constant pressure valve and causes liquid to be continuously delivered to the valve D at a substantially constant low pressure after pump pressure exceeds a predetermined minimum.

From the passage 35, the liquid flows through the valve D and the throttle E to the outlet 13. The valve D causes a drop in pressure between the passage 35 and the chamber 37, and the throttle 15 E causes a drop in pressure between the chamber 37 and the outlet 13.

The flow of liquid through the throttle E follows the law of flow through an orifice. That is, the flow therethrough varies in accordance with 20 variations in the drop in pressure across the orifices E⁴ and is but little affected by a change in the temperature of the oil.

The drop in pressure across the valve D is proportional to the combined resistance of the spring 25 D³ and the bimetallic strip D⁶. The force exerted by the spring D³ upon the ball valve D¹ remains constant but the strip D⁶ responds to variations in the temperature of the oil to increase this force as the temperature rises and to decrease it as the 30 temperature decreases.

Therefore, since the liquid pressure in the passage 35 is maintained substantially constant by the valve C, the valve D will vary the pressure in the chamber 37 inversely to variations in the temperature of the liquid.

Since the flow of liquid through the throttle E is varied in accordance with the drop in pressure across the same, and since the pressure remains constant in the outlet 13 and the pressure in the 40 chamber 37 varies inversely to variations in the temperature of the liquid, the flow through the throttle E will vary inversely to variations in the temperature of the liquid.

Therefore, since the liquid is delivered to the 45 valve D at a substantially constant pressure, the flow therethrough and through the throttle is not affected by variations in pressure but varies solely in response to variations in temperature. Consequently, the valves C and D and the throttle E 50 operate to vary the rate of flow of the bypassed liquid inversely to variations in the slip of the transmission due to variations in temperature, thereby operating to maintain the speed of the motor 15 constant at any given temperature.

The slip of a hydraulic transmission is greatest 55 when the pressure and the temperature of the liquid are the highest and is the least when the pressure and the temperature of the liquid are the lowest. If a transmission could operate at zero pressure, its slip would be zero at zero pressure but it cannot operate at a pressure less than the minimum pressure required to overcome the inertia and friction of its moving parts.

The slip compensator is initially so adjusted 60 that, at the minimum pump pressure and at the lowest temperature under which the transmission is to operate, liquid will be bypassed therethrough at a rate at least as great as the rate of slip when the pressure and temperature of the liquid are at the highest points which will be 65 encountered. Therefore, the pump pistons must move, during a given period of time, a volume of liquid equal to the consumption of the motor, the slip of the transmission and the volume bypassed 70 during that period of time.

The slip compensator is then further adjusted to vary the flow therethrough in accordance with the characteristics of the transmission. Then, as the slip of the transmission varies due to a variation in either the pressure or the temperature of the liquid or to variations in both pressure and temperature, the flow of bypassed liquid is varied at exactly the same rate but inversely thereto, thereby keeping the motor consumption and motor speed constant regardless of variations in the pressure and/or the temperature of the liquid.

It is sometimes desirable to have a small change in speed in response to a variation in the temperature or the pressure of the liquid. This may 15 be accomplished, within the limits of the compensator, by simply adjusting the apparatus to under compensate or to over compensate as desired.

The invention herein set forth is susceptible of 20 various modifications and adaptations without departing from the scope thereof as hereafter claimed.

The invention is hereby claimed as follows:

1. The combination, with a hydraulic motor, a 25 pump normally delivering motive liquid at a rate in excess of the rate required to drive said motor at a predetermined speed, a pressure channel for directing motive liquid from said pump to said motor and a return channel for directing exhaust 30 liquid from said pump to said motor, of a slip compensator connected between said pressure channel and said return channel and comprising means for subtracting liquid from the output of said pump at a limited rate and responsive to 35 variations in pump pressure to vary said limited rate inversely to said variations in pressure, and a second means connected in parallel with the aforesaid means for subtracting liquid from the output of said pump at a limited volumetric rate 40 and responsive to variations in the temperature of the liquid delivered by said pump to vary said volumetric rate inversely to said variations in temperature.

2. The combination, with a hydraulic motor 45 and a pump for supplying liquid to said motor to drive the same and normally delivering liquid at a rate in excess of the rate required to drive said motor at a predetermined speed, of a slip compensator comprising a viscous flow choke and an 50 orifice choke connected in series with each other and with the outlet of said pump and together forming throttling means for subtracting liquid from the output of said pump at limited rates, a pressure inverter connected between said pump and said throttling means for varying the pressure at the inlet to said throttling means inversely to variations in pump pressure, and means for adjusting said choke and said orifice simultaneously.

3. The combination, with a hydraulic motor and a pump for supplying liquid to said motor to drive the same and normally delivering liquid at a rate in excess of the rate required to drive said motor at a predetermined speed, of a slip compensator comprising a choke and an orifice connected in series with each other and with the outlet of said pump and forming throttling means for subtracting liquid from the output of said pump at limited rates, a pressure inverter connected between said pump and said throttling means for varying the pressure at the inlet to said throttling means inversely to variations in pump pressure, means for adjusting said choke and said orifice simultaneously, and means for 70 75 80 85 90 95

varying the relation between said choke and said orifice.

4. The combination, with a hydraulic motor and a pump for supplying liquid to said motor to drive the same and normally delivering liquid at a rate in excess of the rate required to drive said motor at a predetermined speed, of a slip compensator comprising a choke and an orifice connected in series with each other and with the outlet of said pump and forming throttling means for subtracting liquid from the output of said pump at limited rates, a pressure inverter connected between said pump and said throttling means for varying the pressure at the inlet to said throttling means inversely to variations in pump pressure, means connected in parallel with said pressure inverter for subtracting liquid at a limited rate from the liquid delivered by said pump, and temperature responsive means for varying said limited rate inversely to variations in the temperature of said liquid.

5. The combination, with a hydraulic motor and a pump for supplying liquid to said motor to drive the same and normally delivering liquid at a rate in excess of the rate required to drive said motor at a predetermined speed, said pump and motor having a combined slip which varies in accordance with variations in the pressure and the temperature of said liquid, of a slip compensator connected to said pump for subtracting liquid from the output thereof at a limited volumetric rate and having means responsive to variations in pressure to vary said limited rate inversely to said variations in pressure and means responsive to variations in temperature to vary said limited rate inversely to said variations in temperature; said temperature responsive means including a resistance valve having means for varying the resistance thereof in response to variations in the temperature of the liquid delivered thereto, a throttle connected to the outlet of said resistance valve for retarding the discharge of liquid therefrom, and a constant pressure valve connected between said pump and the inlet of said resistance valve and operable to deliver liquid to said resistance valve at a substantially constant pressure after pump pressure exceeds a predetermined minimum.

6. The combination, with a hydraulic motor and a pump for supplying liquid to said motor to drive the same and normally delivering liquid at a rate in excess of the rate required to drive said motor at a predetermined speed, of a slip compensator comprising means for subtracting liquid from the output of said pump at a limited rate and responsive to variations in pump pressure to vary said limited rate inversely to said variations in pressure, and a second means for subtracting liquid from the output of said pump at a limited volumetric rate and responsive to variations in the temperature of the liquid delivered by said pump to vary said volumetric rate inversely to said variations in temperature; said pressure responsive means including a resistance having a choke and an orifice connected in series, and a pressure inverter connected between said pump and said resistance for varying the pressure of the liquid delivered to said resistance inversely to variations in pump pressure.

7. The combination, with a hydraulic motor and a pump for supplying liquid to said motor to drive the same and normally delivering liquid at a rate in excess of the rate required to drive said motor at a predetermined speed, of a slip compensator comprising means for subtracting

liquid from the output of said pump at a limited rate and responsive to variations in pump pressure to vary said limited rate inversely to said variations in pressure, and a second means for subtracting liquid from the output of said pump at a limited volumetric rate and responsive to variations in the temperature of the liquid delivered by said pump to vary said volumetric rate inversely to said variations in temperature; said pressure responsive means including a resistance having a choke and an orifice connected in series and means for adjusting said choke and said orifice simultaneously, and a pressure inverter connected between said pump and said resistance for varying the pressure of the liquid delivered to said resistance inversely to variations in pump pressure.

8. In a slip compensator for connection to a pump to subtract liquid therefrom at a limited volumetric rate and thereby compensate for variations in the slip of said pump, the combination of a resistance valve having means for varying the resistance thereof in response to variations in the temperature of the liquid delivered thereto, a throttle connected to the outlet of said resistance valve for retarding the discharge of liquid therefrom, and a constant pressure valve connected between said pump and the inlet of said resistance valve and operable to deliver liquid to said resistance valve at a substantially constant pressure after pump pressure exceeds a predetermined minimum.

9. In a slip compensator for connection to a pump to subtract liquid therefrom at a limited volumetric rate and thereby compensate for variations in the slip of said pump, the combination of a resistance valve having a spring urging it to closed position and a thermal element coacting with said spring and responsive to variations in the temperature of said liquid to vary the effect of said spring and thereby vary the flow of liquid through said valve in response to variations in the temperature of said liquid, a throttle connected to the outlet of said resistance valve for retarding the discharge of liquid therefrom, and a constant pressure valve connected between said pump and the inlet of said resistance valve and operable to deliver liquid to said resistance valve at a substantially constant pressure after pump pressure exceeds a predetermined minimum.

10. A slip compensator, for connection to a pump to subtract liquid therefrom at a limited volumetric rate and thereby compensate for variations in the slip of said pump, comprising a choke and an orifice connected in series, a pressure inverter connected to said pump and in series with said choke and said orifice and responsive to variations in pump pressure for causing the pressure of the liquid passing through said choke and said orifice to vary inversely to variations in pump pressure, a resistance valve connected to said pump, a spring urging said resistance valve toward closed position, a thermal element coacting with said spring and responsive to variations in the temperature of the liquid for varying the effect of said spring upon said valve, a throttle connected to the outlet of said resistance valve for retarding the discharge of liquid therefrom, and a constant pressure valve connected between said pump and the inlet of said resistance valve for limiting the pressure of the liquid delivered to said resistance valve and operable to maintain substantially constant the pressure of the liquid delivered to said resistance

valve after pump pressure exceeds a predetermined minimum.

11. A slip compensator, for connection to a pump to subtract liquid therefrom at a limited volumetric rate and thereby compensate for variations in the slip of said pump, comprising a choke and an orifice connected in series, means for adjusting said choke and said orifice simultaneously, a pressure inverter connected to said pump and in series with said choke and said orifice and responsive to variations in pump pressure for causing the pressure of the liquid passing through said choke and said orifice to vary inversely to variations in pump pressure, a resistance valve connected to said pump, a spring urging said resistance valve toward closed position, a thermal element coacting with said spring and responsive to variations in the temperature of the liquid for varying the effect of said spring upon said valve, a throttle connected to the outlet of said resistance valve for retarding the discharge of liquid therefrom, and a constant pressure valve connected between said pump and the inlet of said resistance valve for limiting the pressure of the liquid delivered to said resistance valve and operable to maintain substantially constant the pressure of the liquid delivered to said resistance valve after pump pressure exceeds a predetermined minimum.

12. A slip compensator, for connection to a pump to subtract liquid therefrom at a limited volumetric rate and thereby compensate for variations in the slip of said pump, comprising a choke and an orifice connected in series, means for adjusting the relation between said choke and said orifice, a pressure inverter connected to said pump and in series with said choke and said orifice and responsive to variations in pump pressure for causing the pressure of the liquid passing through said choke and said orifice to vary inversely to variations in pump pressure, a resistance valve connected to said pump, a spring urging said resistance valve toward closed position, a thermal element coacting with said spring and responsive to variations in the temperature of the liquid for varying the effect of said spring upon said valve, a throttle connected to the outlet of said resistance valve for retarding the discharge of liquid therefrom, and a constant pressure valve connected between said pump and the inlet of said resistance valve for limiting the pressure of the liquid delivered to said resistance valve.

liquid delivered to said resistance valve and operable to maintain substantially constant the pressure of the liquid delivered to said resistance valve after pump pressure exceeds a predetermined minimum.

13. A slip compensator, for connection to a pump to subtract liquid therefrom at a limited volumetric rate and thereby compensate for variations in the slip of said pump, comprising a choke and an orifice connected in series, means for adjusting said choke and said orifice simultaneously, means for adjusting the relation between said choke and said orifice, a pressure inverter connected to said pump and in series with said choke and said orifice and responsive to variations in pump pressure for causing the pressure of the liquid passing through said choke and said orifice to vary inversely to variations in pump pressure, a resistance valve connected to said pump, a spring urging said resistance valve toward closed position, a thermal element coacting with said spring and responsive to variations in the temperature of the liquid for varying the effect of said spring upon said valve, a throttle connected to the outlet of said resistance valve for retarding the discharge of liquid therefrom, and a constant pressure valve connected between said pump and the inlet of said resistance valve for limiting the pressure of the liquid delivered to said resistance valve and operable to maintain substantially constant the pressure of the liquid delivered to said resistance valve after pump pressure exceeds a predetermined minimum.

14. The combination, with a hydraulic motor and a pump for supplying liquid to said motor to drive the same and normally delivering liquid at a rate in excess of the rate required to drive said motor at a predetermined speed, of a slip compensator comprising a resistance connected to the outlet of said pump and including a choke and an orifice forming throttling means for subtracting liquid from the output of said pump at limited rates, a pressure inverter connected between said pump and said resistance for varying the pressure at the inlet to said resistance inversely to variations in pump pressure, means for varying the cross-sectional area of said choke and the cross-sectional area of said orifice simultaneously, and means for adjusting said orifice independently of said choke.
